KEY RETAINER

Samuel Segal, New York, N. Y., assignor to Pioneer Suspender Company, Philadelphia, Pa., a corporation of Pennsylvania

Application April 15, 1946, Serial No. 662,266

15. Claims. (Cl. 70—456)

1

The invention deals with key retainers of the type having a slotted bead for desirably and swingably sustaining key holding means which may be in the form of a headed hanger, or headed rivet swingably sustaining the hanger. The dominant object of the invention is realized in the provision of a rectilinear closure or backing slidably guiding a support having a slotted beaded portion for removably sustaining key holding means and in the provision of intervening actuating means interposed between the support and backing and adapted to be effectively operated by laterally extending and conveniently accessible means for either shifting the slotted beaded portion away from the backing and thus render the slots accessible for threading the key holding means therein or for retracting the slotted beaded portion towards the backing whereby the latter blocks the slots of the beaded portion to preclude the removal of the key holding means therefrom. Specifically the invention has as another object the provision of a serviceable key retainer of the type alluded to wherein the actuating means is characterized by a cam slot cooperating with pin means projecting from the support whereby upon the manipulation of the laterally extending means or manipulator the support is displaced linearly either away from or towards the backing to open or close the retainer respectively. The invention has as a further object the provision of an arcuate overhanging bead on the support defining spaced and arcuate relatively wide teeth having terminal portions adapted to be removably received by spaced notches interrupting the backing. The invention further comprehends as an object the provision of spaced projections or lugs on the backing removably received in the slots of the support, that is, between the terminals of the arcuate and overhanging teeth to block the slots or interlock with the teeth to preclude the withdrawal of the key holding means. Other important objects, features, and functional and structural advantages of the invention will appear from the following detailed specification taken with the accompanying drawings wherein:

Fig. 1 is a front view of the key retainer according to my invention, illustrating the retainer closed.

Fig. 2 is a rear view of Fig. 1.

Fig. 3 is a plan view of Fig. 1.

Fig. 4 is a view similar to Fig. 1, however illustrating the retainer opened.

Fig. 5 is a rear view of Fig. 4.

Fig. 5^a is a transverse sectional view on the line 5^a—5^a of Fig. 5.

Fig. 6 is an enlarged transverse sectional view on the line 6—6 of Fig. 2.

Fig. 6^a is a fragmentary and front perspective view of the retainer shown closed.

2

Fig. 7 is a fragmentary and rear projective view of the retainer shown closed.

Fig. 8 is a view similar to Fig. 7 illustrating the retainer in an opened relation.

Fig. 9 is an enlarged transverse sectional view on the line 9—9 of Fig. 2 however illustrating the retainer attached to the leather panel illustrated in Fig. 1.

Fig. 10 is a view similar to Fig. 9 however taken on the line 10—10 of Fig. 2.

Fig. 11 is a view similar to Fig. 10 but illustrating the retainer open and the flexible panel bent rearwardly to permit withdrawal of key holding means, and

Fig. 12 is a perspective view of the intervening actuator for shifting the beaded and slotted support relative to the closure or backing.

Illustrative of the embodiment disclosed, the key retainer is generally denoted R and comprises a support S and a backing or closure B. The support S is in the form of a rectilinear plate having an upper and arcuate beaded portion BD interrupted by a plurality of slots 10 defining the spaced and relatively wide teeth 11 provided with the free terminals 12. The sides of the support S have rearwardly disposed and inwardly turned flanges 13 defining channel shaped means with the support S for rectilinearly and slidably guiding the offset vertical margins 14 of the backing B. By reason of this construction, the body 15 of the backing which in fact is a rectilinear plate is spaced from the support, thus characterizing therewith the gap 16 (Figs. 6 and 10). The offset margins 14 (Fig. 5^a) are tracks straddled by the inwardly turned flanges 13 of the support S for controlling linear displacement of the latter which appropriately carries a pin 17 in the form of a set screw having its shank threadably secured in the body of the support.

Pin 17 projects into and is adapted to be driven by the walls of the cam slot 18 in the shank 19 of the actuator broadly indicated 20 (Fig. 1) which has an offset arm or portion 21 having the accessible finger gripping portion or manipulator 22. The actuator 20 is an intervenor closely but movably confined in gap 16. More specifically the actuator 20 is also slidably guided between the spaced walls 23 (Figs. 2 and 5) of the gap 24 interrupting one of the offset margins 14 of the slidably guided backing B. Also slidably and rectilinearly guiding the actuator 20, that is, the shank 19 thereof, are the spaced projections 25 (Figs. 1 and 9) struck out of the backing or closure B. The pin 17 although fixedly carried by the support S also in part projects into the circular relief opening 26 in the backing B.

The free terminals 12 of the spaced arcuate teeth 11 of the overhanging but interrupted bead of the support S are removably received in the spaced notches 27 at the top margin of the back-

60 spaced notches 27 at the top margin of the back-

ing B which may be said to embody the spaced projections 28 adapted to be removably straddled by the spaced terminals 12 of the teeth 11 and adapted to close or block off the slots 10 at the free terminals 12 hence precluding the insertion of the key holding means broadly designated KH and K'H' into the slots 10 of the bead at a time when the support S and the actuator 20 are retracted as shown in Figs. 1, 6^a and 7 in which instance the retainer may be said to be closed.

In the closed relation of the retainer, the enlarged head 30 of a rivet 31 of the key holder KH and the head 31' of the key holder K'H' are prevented from withdrawal or removal from the slots 10 of the bead BD. By applying outwardly directed finger pressure on lug 22 of the actuator 20 (Fig. 1), the latter is pulled outwardly, ultimately causing the inclined wall 18' of the cam slot 18 to abut and drive pin 17, thus raising the latter. This action elevates or drives the support S above the backing B (Figs. 4, 5, 8 and 11). Or in other words, the retainer is now opened and the heads 30 or 31' of the key holding means may be removed or inserted into the slots of the bead and if inserted, to interlock with the bead and be sustained thereby.

With the retainer open the latter may be conveniently closed by sliding the actuator or driving means 20 into the retainer, that is by retracting the actuator, in which instance the upper cam face 18" drives pin 17 downwardly, and consequently support S is slidably retracted to its closed position. However on leaving the inclined face 18" the horizontal walls 18^a of the cam slot 18 movably and closely embrace pin 17, thus frictionally locking or braking the latter so that when the retainer is fully closed, it is resisted from accidentally opening.

As illustrated in Fig. 1, the key holder KH may be said to comprise the rivet 30 swingably sustaining the hanger H whereas the key holding means K'H' is merely a hanger or hook of a conventional design. In either case, however, the key holders desirably sustain a key K.

The retainer according to the invention may be quickly fastened to a leather panel P by rivets 32 and when the retainer is opened (Fig. 11), the upper end of the flexible panel may be bent to permit removal or insertion of the key holding means between the teeth 11 of the overhanging and interrupted bead BD.

For purposes of specification the support and backing may be considered complementary plates displaceable relative to one another for opening or closing of the key retainer.

Various changes may be made in details of construction and arrangement of parts without departing from the spirit of the invention or sacrificing any of the advantages thereof inherent therein.

I claim:

1. In a key retainer, a backing, a support, means for slidably guiding said support relative to said backing, an actuator interposed between said backing and said support and having a cam slot, and driven means projecting from said support and extending into said slot for displacing said support relative to said backing.

2. In a key retainer, a backing, a support having a slotted bead, means for slidably guiding said support relative to said backing, an actuator interposed between said backing and said support and having a cam slot, and driven means projecting from said support and extending into said slot for displacing said bead relative to said

backing to elevate or lower said bead relative to said backing.

3. In a key retainer, a backing, a support having a slotted bead, means for slidably guiding said support relative to said backing, an actuator interposed between said backing and said support and having a cam slot, driven means projecting from said support and extending into said slot for displacing said bead relative to said backing, and a manipulator carried by said actuator.

4. In a key retainer, a backing, a support having a slotted bead, means for slidably and vertically guiding said support relative to said backing, an actuator interposed between said backing and said support and having a cam slot, driven means projecting from said support and extending into said slot for displacing said bead relative to said backing, means for slidably guiding said actuator, and a manipulator carried by said actuator and extending laterally of said support and backing.

5. In a key retainer, a backing, a support having a slotted bead defining spaced teeth having free terminal portions, means for slidably guiding said support relative to said backing, an actuator interposed between said backing and said support and having a cam slot, pin means projecting from said support and extending into said slot for displacing said terminal portions relative to said backing, and a manipulator carried by said actuator for displacing the latter.

6. In a key retainer, a backing, a support having a slotted bead defining spaced teeth having free terminal portions, means for slidably guiding said support relative to said backing, an actuator interposed between said backing and said support and having a cam slot, means for slidably guiding said actuator, driven means projecting from said support and extending into said slot for displacing said terminal portions relative to said backing, and accessible manipulating means for operating said actuator to displace said terminal means relative to said backing.

7. In a key retainer, a backing, a support having a slotted bead defining spaced teeth having free terminal portions, means for slidably guiding said support relative to said backing, an actuator interposed between said backing and said support and having a cam slot, driven means projecting from said support and extending into said slot for displacing said terminal portions relative to said backing, a manipulator for operating said actuator, and means for braking said driven means to preclude displacement of said support relative to said backing.

8. In a key retainer, a backing having spaced projections defining spaced notches, a support having a bead including spaced slots for removably receiving said projections and including spaced teeth having free terminal portions removably received by said notches, means for slidably guiding said support relative to said backing, an actuator interposed between said backing and said support and having a cam slot, and driven means projecting from said support and extending into said slot for displacing said terminal portions relative to said notches.

9. In a key retainer, a backing having spaced projections defining spaced notches, a support having an arcuate bead including spaced and vertically arranged slots for removably receiving said projections and including spaced teeth having free terminal portions removably received

by said notches, means for slidably guiding said support relative to said backing, an actuator interposed between said backing and said support and having a cam slot, a pin projecting from said support and extending into said slot for displacing said support relative to said backing, and a manipulator carried by said actuator for operating the latter to remove said slots from said projections and said terminal means from said notches.

10. In a key retainer, a plate having spaced projections defining spaced notches, a plate having a bead including spaced slots for removably receiving said projections and including spaced teeth having free terminal portions removably received by said notches, means to slidably guide one of said plates relative to the other, an actuator interposed between said plates and having a cam slot, driven means projecting from one of said plates and extending into said slot for displacing one of said plates relative to the other, and a manipulator carried by said actuator for operating the latter to remove said slots from said projections and said terminal means from said notches.

11. In a key retainer, a backing having spaced projections defining spaced notches, a support having a bead including spaced slots for removably receiving said projections and including spaced teeth having free terminal portions removably received by said notches, means for slidably guiding said support relative to said backing, an actuator interposed between said backing and said support and having a cam slot, driven means projecting from said support and extending into said slot for displacing said support relative to said backing, a manipulator carried by said actuator, and means for braking said driven means to resist displacement of said actuator relative to said support.

12. In a key retainer, a backing, a support having a bead including spaced slots, means for slidably guiding said support relative to said backing, an actuator interposed between said backing and said support and having an elongated slot comprising an inclined portion and a substantially horizontally arranged portion, driven means projecting from said support and extending into said slot and cooperating with said inclined portion for displacing said support relative to said backing, and a manipulator for driving said actuator.

13. In a key retainer for sustaining key holding means, a backing, a support having a bead including spaced slots for removably receiving said key holding means, means for slidably guiding said support relative to said backing, an actuator interposed between said backing and

said support and having an elongated cam slot comprising an inclined portion and a substantially horizontal portion in communication, driven means projecting from said support and extending into said slot and cooperating with said inclined portion for displacing said support relative to said backing and cooperating with said horizontal portion to resist displacement of said support relative to said backing, and manipulating means carried by said actuator.

14. In a key retainer for sustaining key holding means, a backing, a support having a bead including spaced vertically disposed slots for removably receiving said key holding means, channeled shaped means carried by said support and movably straddling said backing for slidably guiding said support relative to said backing, an actuator interposed between said backing and said support and having an elongated cam slot comprising an inclined portion and a substantially horizontal portion in communication, driven means projecting from said support and extending into said slot and cooperating with said inclined portion for displacing said support relative to said backing and cooperating with said horizontal portion to resist displacement of said support relative to said backing, and manipulating means carried by said actuator.

15. In a key retainer for sustaining key holding means, a backing, a support having a bead including spaced slots for removably receiving said key holding means, track means for slidably guiding said support relative to said backing, an actuator interposed between said backing and said support and having an elongated intermediately disposed cam slot comprising an inclined portion and a substantially horizontal portion in communication, pin means projecting from said support and extending into said slot and cooperating with said inclined portion for vertically displacing said support relative to said backing and cooperating with said horizontal portion to resist displacement of said support relative to said backing, and manipulating means carried by said actuator and disposed at corresponding sides of said support and backing.
